(57) **CLAIM**

The ornamental design for a portable electronic article surveillance scanner, detector, and reactivator, as shown and described.

DESCRIPTION

FIG. 1 is a right, rear perspective view of the design showing a portable electronic article surveillance scanner, detector, and reactivator;

FIG. 2 is a left, rear perspective view thereof;

FIG. 3 is a left, front perspective view thereof; and,

FIG. 4 is a left elevational view thereof.

The broken lines showing of a keypad in FIG. 3 is for illustrative purposes only and forms no part of the claimed design.

1 Claim, 4 Drawing Sheets

FIG. 1

FIG. 2

FIG. 3

FIG. 4
